UNITED STATES PATENT OFFICE

JOSEPH BURGER, OF BROOKLYN, NEW YORK

DESIGN FOR A SHOE-HEEL COVER

Application filed August 9, 1930. Serial No. 36,617. Term of patent 14 years.

To all whom it may concern:

Be it known that I, JOSEPH BURGER, a citizen of the United States, residing at Brooklyn, county of Kings, and State of New York, have invented a new, original, and ornamental Design for a Shoe-Heel Cover, of which the following is a specification, reference being had to the accompanying drawing, forming part thereof.

The single view in the drawing is a plan view of a shoe heel cover embodying the design.

I claim:

The ornamental design for a shoe heel cover, substantially as shown.

JOSEPH BURGER.
